(57) **CLAIM**

The ornamental design for a rearview mirror housing, as shown and described.

DESCRIPTION

FIG. 1 is a front perspective view of a rearview mirror housing according to a first embodiment of our design; FIG. 2 is an enlarged detail view thereof showing area 2, as indicated in FIG. 1;

FIG. 3 is a back perspective view thereof;

FIG. 4 is an enlarged detail view thereof showing area 4, as indicated in FIG. 3;

FIG. 5 is a front elevation view thereof;

FIG. 6 is a back elevation view thereof;

FIG. 7 is an enlarged detail view thereof showing area 7, as indicated in FIG. 6;

FIG. 8 is a right side elevation view thereof;

FIG. 9 is an enlarged detail view thereof showing area 9, as indicated in FIG. 8;

FIG. 10 is a left side elevation view thereof;

FIG. 11 is a top plan view thereof;

FIG. 12 is a bottom plan view thereof;

FIG. 13 is an enlarged detail view thereof showing area 13, as indicated in FIG. 12;

FIG. 14 is a front perspective view of a rearview mirror housing according to a second embodiment of our design; FIG. 15 is an enlarged detail view thereof showing area 15, as indicated in FIG. 14;

FIG. 16 is a back perspective view thereof;

FIG. 17 is an enlarged detail view thereof showing area 17, as indicated in FIG. 16;

FIG. 18 is a front elevation view thereof;

FIG. 19 is a back elevation view thereof;

FIG. 20 is an enlarged detail view thereof showing area 20, as indicated in FIG. 19;

FIG. 21 is a right side elevation view thereof;

FIG. 22 is an enlarged detail view thereof showing area 22, as indicated in FIG. 21;

FIG. 23 is a left side elevation view thereof;

FIG. 24 is a top plan view thereof;

FIG. 25 is a bottom plan view thereof; and,

FIG. 26 is an enlarged detail view thereof showing area 26, as indicated in FIG. 25.

The dash-dash broken lines depict portions of the article that form no part of the claimed design.

The dash-dot broken lines, adjacent to the un-shaded areas, represent bounds of the claimed design and form no part of

(Continued)

the claimed design. The dash-dot-dot broken lines show the boundaries of the enlarged detailed views and form no part of the claimed design.
